UNITED STATES PATENT OFFICE.

LEWIS B. BRIDGES, OF BROOKLYN, NEW YORK, ASSIGNOR TO CORONA TYPEWRITER COMPANY, INC., OF GROTON, NEW YORK, A CORPORATION OF NEW YORK.

FOLDING TYPEWRITING MACHINE.

Original application filed March 10, 1919, Serial No. 281,631. Divided and this application filed May 15, 1920. Serial No. 381,707.

To all whom it may concern:

Be it known that I, LEWIS B. BRIDGES, a citizen of the United States, and resident of the borough of Brooklyn, in the county of 5 Kings, city and State of New York, have invented certain new and useful Improvements in Folding Typewriting Machines, of which the following is a specification.

One of the objects of this invention is to 10 provide a folding typewriting machine having the appearance of a large standard machine when extended, and so constructed that the cubical dimensions thereof may be reduced approximately 50%, the keyboard and 15 other parts being foldable to reduce the length of the machine from front to rear substantially 50% without increasing the width or height of the machine and in such manner as to maintain the type basket, carriage, ribbon mechanism, escapement mechanism, and universal bar mechanism in upright positions at all times, thus adapting the folded machine to fit in an elongated rectangular case with the base of the machine 20 resting on the bottom of the case and permitting the machine to be conveniently carried in its case with the major portion thereof and the principal mechanisms in an upright position.

Another object of the invention is to provide a type-bar action for compactible typewriting machines having key-supporting levers operatively connected to actuate the type bars and foldable bodily in their entirety relatively to the type bars, without 25 breaking the mechanical connections between the levers and type bars, to a vertical position in front of the type bars.

Another object of the invention is to provide a type-bar action in which key-supporting levers are employed for actuating the type bars so constructed that the keys will be supported in stepped rows or banks, will be easy to operate, will have a uniform 40 throw, and may be folded bodily upward and rearward with their supporting levers about an axis close to the base of the machine and adjacent the rear edge of the keyboard.

A further object of the invention is to provide a folding type bar action for compactible typewriting machines in which the keys are supported by pivoted levers mechanically 45 connected with the type bars at all times,

the key supporting levers being so constructed and mounted and so connected with the type bars that the levers may be folded bodily upward and rearward from horizontal to vertical positions, and the keys being so mounted on the levers that short levers of uniform length may be employed for supporting the keys in banks without causing undesirable tilting of the keys when the keys are depressed sufficiently to move the type bars to the printing point. 55

Another important object of the invention is to provide a type bar action easy to operate, having a light and uniform key touch, and so constructed that the keyboard may be folded from its normal horizontal position to a vertical position with a portion of the keyboard forward of the type-bar rest and a portion of the keyboard below the type-bar rest, whereby the length of the machine from front to rear may be reduced to a minimum when the machine is collapsed without increasing the height of the machine. 70 75

Further highly important objects of the invention are to provide a typewriting machine having a foldable type-bar action so constructed that the keyboard may be folded in compact relation with the type bars without increasing the height of the machine and without the necessity of providing sectional key levers having parts foldable relatively to each other and without breaking the operating connections between the keys and type bars. 80 85

This application is a division of my co-pending application, Serial No. 281,631, filed March 10, 1919. 90

In the drawings, Fig. 1 is a vertical sectional view of the machine in its normal extended operative position; 95

Fig. 2 a similar view showing the machine compacted;

Fig. 3 a fragmentary vertical transverse sectional view;

Fig. 4 a fragmentary plan view; 100

Fig. 5 a detail view showing part of the case shift mechanism;

Fig. 6 a detail vertical section showing the space bar mechanism;

Fig. 7 a detail side elevation showing part of the case shift mechanism; and 105

Fig. 8 a view showing the different forms of printing key stems.

The main or relatively stationary frame part is formed with side walls 1 and a rear wall 2, the side and rear walls being cut away as shown, and the front of said frame part being open. The higher parts of the side walls 1 at the front of the machine are connected by a top or finishing plate 3, and said side walls are also connected adjacent their lower edges by a transverse plate or bar 4.

An upwardly and rearwardly foldable keyboard frame part 5, substantially U-shaped in plan view, is pivotally held to the side walls 1 by bolts 6 which pass through the side walls 1 at points closely adjacent the bottom of the machine frame. Clamping or thumb nuts 7 are threaded on the outer ends of bolts 6 and serve when tightened to lock the keyboard frame part 5 in either its normal horizontal position or its folded vertical position. The relatively stationary main frame part is preferably provided with rubber feet 8 at each corner thereof. The keyboard frame part is preferably provided with two rubber feet 9 at the front corners thereof, and the side walls of the keyboard frame part are preferably formed with lugs 5^a adapted to engage plate 4 when the keyboard frame part is folded, 30 to arrest said frame part in the position shown in Fig. 2.

The printing keys 10 are arranged in three rows or banks and are supported on the upper ends of three rows of key stems 11, 12 and 13. The lower portions of the key stems of all three rows are arranged in alignment transversely of the keyboard frame part and extend vertically. The upper portion of each key stem 11 extends 40 upwardly and rearwardly, the upper portion of each key stem 12 extends vertically and is offset slightly forwardly of the lower portion thereof and the upper portion of each key stem 13 extends forwardly and upwardly from the lower vertically disposed portion thereof. The key stems are supported on the forward ends of two series of superposed parallel rows of levers extending fore and aft of the keyboard frame part. The levers 14 of one row are pivotally supported intermediate their ends on a common fulcrum rod or wire 15 and extend through kerfs in a bar 16 held to the keyboard frame part. The levers 17 of the lower row extend 50 through kerfs in bar 16 and are pivotally supported on a common fulcrum wire or rod 18. The vertical portion of each key stem is connected by pivot pins 19 and 20 with the forward ends of two superposed levers 14 and 17 and the rear ends of each pair of superposed levers 14 and 17 are connected by one of a series of vertical links 21 arranged in alignment transversely of the keyboard frame part. A series of coil 60 springs 22, held to the front cross-bar of the

keyboard frame part at their forward ends and held to lugs 23 on levers 17 at their rear ends, serve to return the key stems to their normal positions after each depression of a key, the upper edges of the forward portions of levers 17 normally engaging the bottoms of the kerfs in bar 16 at the forward edge of the under side of each bar, and the upper edges of the rear portions of said levers being normally spaced 70 from the bottoms of the kerfs, as shown in Figs. 1 and 2.

Each link 21 is formed with a rearwardly projecting lug 24 adjacent its lower end, to which the forward end of one of a series of links 25 is connected. The points of connection of all of the links 25 with lugs 24 on links 21 are in alignment transversely of the machine and coincident with the point of fold of the keyboard frame part about 85 the pivot bolts 6, the springs 22 serving to normally maintain said points of connection in alignment with bolts 6 or the pivotal axis of the keyboard frame part. The rear ends of links 25 are connected with the lower 90 ends of a series of depending levers 26 pivotally held at their upper ends to a common fulcrum rod 27 which is secured at its ends to the side walls 1 of the main frame part. Each lever 26 is connected by a link 95 28 with one of a series of levers 29 pivotally held at their lower ends to a common fulcrum rod 30 which is secured at its ends to the side walls 1 of the stationary frame part. The levers 29 increase in length from the center toward either side of the machine, and each of said levers is connected at its upper end by a link 31 with a downwardly and rearwardly extending lug 32^a formed on its associated type-bar 32.

The type-bars 32 are pivotally held at their rear ends in a type segment 33 by a common pivot wire 34, and the forward ends of said type bars are normally supported on a type rest 35 held to the type segment by a pair of rods or bars 36. The type segment is formed with end portions 37 extending through and slidable vertically in slots 38 formed in two brackets 39 which are held to the inner side of the rear wall 2 of the main frame part. The slots 38 are closed at the top and bottom to limit the up-and-down movement of the segment, and the lower edges of the end portions 37 of the segment normally rest at the bottoms of the slots and support the segment in its normal lower-case position. At the outer sides of brackets 39 the end portions 37 are formed with stub shafts 40 on each of which is mounted a 110 roller 41.

Each type bar 32 is preferably provided with three characters, as shown, and the segment 33 is adapted to be shifted upwardly relatively different distances to middle (or cap) case position and upper (or fig.) case 125 130

position. The middle-case shift key 42 is mounted on a key stem 43 similar to the key stems 13, and the upper-case shift key 44 is mounted on a key stem 45 similar to the key stems 12. The key stems 43 and 45 are each supported on the forward ends of pairs of superposed levers 14^a and 17^a similar to levers 14 and 17, said levers being fulcrumed on rods 15 and 18 and the rear ends thereof being connected by vertical links 21^a similar to the links 21. The links 21^a are formed with lugs similar to lugs 24 on links 21 to which the forward ends of two links 46 and 47 are connected at points in alignment with the points of connection of links 25 with the lugs 24. Link 47 is pivotally connected with the lower end of a rock arm 48 fixed on a rock shaft 49 which is journaled at its ends in the side walls 1 of the stationary frame part. Link 46 is pivotally connected with the lower end of a rock arm 50 fixed to a tubular rock shaft or oscillating sleeve 51 embracing the central portion of rock shaft 49 and revoluble independently thereof. Two similarly shaped cams 52 are held to shaft 49 at opposite sides of the type segment, one cam being normally in engagement with each roller 41, and two cams 53 having a shorter throw than cams 52 are fixed on sleeve 51, one cam 53 also being normally in engagement with each roller 41. It will be obvious that when shift key 42 is depressed the segment will be moved upwardly to vary the relation between the type bars 32 and the platen 54, and that when shift key 44 is depressed the segment will be moved upwardly a greater distance than that imparted through the instrumentality of the key 42 and the cams 53 actuated thereby. A suitable spring (not shown) is provided to assist in returning the segment to its normal position.

The platen 54 is mounted on a carriage 45 traveling on a carriage bed 56. The bed 56 is rigidly held at its ends to the rear ends of a pair of forwardly extending bars 58. The bed and bars form a substantially U-shaped frame for supporting the carriage 50 and associated devices, and said bed and bars are preferably formed integrally, the bed being formed with depending portions 57 at its ends connected with the inner faces of the bars. The ends of the carriage bed 56 are parallel with and preferably a little inside the vertical plane of the inner faces of bars 58. Bars 58 are slidably supported and guided in ways 59 which may be formed by off-setting portions of the side walls 1, 60 as shown, or in any other suitable manner. The U-shaped frame formed by bed 56 and bars 58 is normally held in a rearwardly extended position, as shown in Figs. 1 and 4, to support the platen at the rear and above 65 the main frame part in cooperative relation with the type bars 32, and is adapted to be locked in this position by clamping bolts 60 which extend through apertures in the side walls 3 and through elongated horizontal slots 61 in the bars 58. Suitable thumb nuts 62 are threaded on the outer ends of the clamping bolts 60.

Adjacent their forward ends bars 58 are each formed with a lateral extension or inwardly projecting bracket 63, on which brackets the spindles or shafts 64 of ribbon spools 65 are mounted. An escapement wheel 66 is journaled on a bracket 67 extending upwardly at the rear of the platen and held at its forward end to the under side of the carriage bed 56. A universal bar 68 curved to conform with the arc of the segment 33 is rigidly held to the forward ends of a pair of bars 69. The bars 69 carrying the universal bar 68 are supported to move 85 forwardly and rearwardly by two pairs of rock arms 70 and 71 whose upper ends are rigidly held to rock shafts 70^a and 71^a journaled in suitable bearings formed on the brackets 67. The universal bar 68 is normally held in the forwardly extended position shown in Fig. 1 by means of a suitable spring, and is adapted to be engaged and moved rearwardly by the type bars 32 when the type bars are moved upwardly and 90 rearwardly to the printing point. Suitable mechanism, such as shown in the patent to Latta, No. 1,222,550, dated April 10, 1917, may be provided for operating the carriage escapement and for feeding and vibrating the 100 ribbon, such mechanism being mounted on the U-shaped frame part and operatively connected with the universal bar 68.

The space bar 72 is supported on the forward ends of three angle arms 73, the vertically extending rear portions 73^a of which are each pivotally held to the forward ends of a pair of superposed parallel levers 74 and 75 similar to levers 14 and 17 supporting the key stems. The levers 74 and 75 of each 105 pair are connected at their rear ends by a vertical link 76 similar to links 21. The link 76 connecting the rear ends of the central pair of superposed levers 74 and 75 is formed with an ear or lug 77 similar to lugs 110 24 on links 21, and the forward end of a link 78 similar to links 25 is pivotally connected with said lug 77 in alignment with the points of connection of the forward ends 115 of links 25 with lugs 24, and in alignment 120 with the pivotal axis of the key-board frame part 5. The link 78 is connected at its rear end, in the same manner as links 25 are connected with the type bars, with a blank type 125 bar or universal-bar-operating lever 79 pivotally supported midway of the type segment 33 on the fulcrum wire 34. The free end of the blank type bar 79 normally rests on the type bar rest 35. It will be obvious 130 that by depressing the space bar the blank

type bar will be moved upwardly and rearwardly and will actuate the universal bar to letter-space the carriage without printing.

The pivoted keyboard frame part 5 is operatively connected with the U-shaped horizontally slidable frame part which supports the carriage, platen, universal bar, ribbon mechanism and escapement mechanism, to move the slidable frame along the guideways 59 when the keyboard frame part is shifted. The keyboard frame and the U-shaped frame are movable simultaneously toward and from each other to and from their compacted or folded positions through the medium of a pair of links 80 and a pair of levers 81. The levers 81 are pivotally held intermediate their ends to the side walls 1 of the stationary main frame part. The upper ends of said levers have pin-and-slot 20 connections 83 with the forward ends of the bars 58, and the lower ends of the levers are pivotally connected at 84 with the rear ends of the links 80. The forward ends of links 80 are pivotally connected at 85 with the side 25 walls of the keyboard frame part 5 at a point above the pivot point 84 and above the pivot bolts 6 of the key-board frame part.

It will be obvious that the keyboard frame part may be folded upwardly and rearwardly about pivots 6 from its normal forwardly extended horizontal position to a compact vertical position within the forward part of the main frame without any portion of the keyboard frame 35 projecting above the main frame, and that when the keyboard frame is folded the bars 58 will be moved horizontally forward along the ways 59 by links 80 and levers 81, thus moving the carriage, platen, universal 40 bar, ribbon mechanism and escapement mechanism forwardly from their normal positions to more compact positions over the type bars and closer to the keyboard. It will be observed also that the ribbon spools move 45 to a compact position below the top plate 3 of the main frame and above the plane of the type basket, into close relation with the lowest part of the keyboard, that the lower part of the keyboard is moved to a compact 50 position in front of the ribbon spools and type-bar rest, while the higher part is moved to a compact position below the type-bar rest, and that all of the parts mounted on the horizontally slidable frame part and the upwardly swinging frame part are brought 55 within the vertical planes of the front and rear ends of the main frame part without increasing the height of the machine when folded. The various parts of the machine 60 are thus folded into very compact relation and in such a way that the machine when folded assumes an elongated rectangular form, with the more delicate parts, such as the carriage, ribbon mechanism, escapement 65 mechanism, universal bar and type basket, in

the same planes as they occupy when in their normal extended operative positions. By this arrangement the cubical dimensions of the machine may be reduced approximately 50% and the folded machine may be carried 70 in a conveniently portable, elongated, rectangular case with the base of the main frame part resting on the bottom of the case, and with the delicate mechanisms above specified in their normal planes, thus avoiding any tendency to strain or disarrange parts of said mechanisms when the machine is carried in its enclosing case. 75

Any suitable or known means, such, for example, as integral hubs on the levers or 80 separate spacing sleeves on the fulcrum rods, may be employed for spacing the levers 26 and 29 on their fulcrum rods 27 and 30. It will be obvious also that the locking bolts 60 and slots 61 may be omitted if desired. 85

What I claim is:

1. A foldable key action for compactible typewriting machines comprising a type-bar, a keyboard support movable from a normal substantially horizontal position to a substantially vertical position closer to and wholly in front of said type-bar, a relatively short lever fulcrumed intermediate its ends on said support and movable bodily as an entirety to an upright position therewith, a key operatively connected with the forward end of said lever for rocking the same, and means forming a constantly maintained mechanical operating connection between said lever and the type-bar foldable at a point 100 in the rear of the fulcrum of said lever. 95

2. A foldable type bar action for a compactible typewriting machine comprising a relatively stationary support, a type bar fulcrumed on said support to move upwardly and rearwardly to the printing point, a keyboard support foldable upwardly and rearwardly to a vertical position in front of the type bar, a relatively short lever fulcrumed intermediate its ends on said keyboard support, a key connected with the forward end of said lever for rocking the same, a link having a foldable operating connection with said lever at a point in rear of the fulcrum of the lever and coincident 110 with the point of fold of the keyboard support, a second lever pivotally supported at its upper end on the stationary support and having its lower end connected with said link, a third lever pivotally supported at 115 its lower end on the stationary support and extending parallel with said second lever, a link connecting the second and third levers intermediate their ends, and a link connecting the upper end of the third lever with 120 the rear end of the type bar at a point below the fulcrum of the type bar. 125

3. In a compactible typewriting machine, the combination of a key-controlled part, an operating key therefor foldable relative- 130

ly to said part, a key stem supporting said key, a pair of superposed levers extending longitudinally of the machine and pivotally connected at their forward ends with the 5 key stem, a link connecting the rear ends of said levers, a support on which said levers are fulcrumed intermediate their ends foldable upwardly and rearwardly about a pivotal axis close to the base of the machine 10 toward the key-controlled part to thereby carry said superposed levers bodily to an upright position wholly in front of the type bars, and a foldable operating connection between said link and the key-controlled part.

15 4. The combination of a series of type bars pivoted on a curved line, a series of upwardly extending levers increasing in length from the center to the sides of the system and pivoted on a straight line at their lower 20 ends, a series of links connecting the upper ends of said levers with the type bars, a second series of levers of equal length pivoted at their upper ends on a straight line, a series of links connecting the two series 25 of levers intermediate their ends, a series of key-supporting levers fulcrumed intermediate their ends, a series of keys supported by said key-supporting levers, and a series of links connecting the rear ends of 30 the key-supporting levers with the lower ends of said second series of levers.

35 5. In a typewriting machine, the combination of a main frame part, type bars mounted on the main frame part fore and aft of the machine, a keyboard frame part pivotally connected adjacent its rear end with the forward end of the main frame part adjacent the base of the machine and foldable to an upstanding position close to 40 the type-bars, key-operated levers pivotally supported on the keyboard frame part fore and aft of the machine with their rear ends adjacent the pivotal axis of the keyboard frame part, said key-operated levers 45 being movable bodily with the keys to a position wholly in front of the type-bars, keys connected with the forward ends of said levers, and operating connections between the rear ends of said levers and the 50 type bars foldable at points coincident with the pivotal axis of the keyboard frame part.

55 6. In a compactible typewriting machine,

the combination of type bars, a keyboard support foldable upwardly and rearwardly to an upstanding position in front of and close to the type bars, keys, short individual 55 rocking key supports lying wholly below the keys and extending fore and aft of the machine and fulcrumed intermediate their ends on the keyboard support to move up 60 and down uniform distances and be carried over bodily to an upright position when the keyboard is folded to non-use position, and individual operating connections between the key supports and their associated type 65 bars pivotally held at the forward ends thereof to the rear ends of the key supports in alignment with the pivotal axis of the foldable keyboard support.

7. In a compactible typewriting machine, 70 the combination of a main frame part, type bars mounted on the main frame part, a keyboard frame part hinged to the main frame part adjacent the base of the machine to fold upwardly and adapted to come to 75 rest in an upstanding position wholly in front of the type bars, keys, rocking devices fulcrumed on the keyboard frame part supporting the keys in stepped rows to move up and down uniform distances without tilting, said rocking devices being movable in 80 their entirety with the keyboard frame part to upright positions in front of the type-bars when the keyboard is raised to non-use position, and foldable constantly maintained 85 operating connections between the rocking devices and type bars.

8. In a compactible typewriting machine, the combination of type bars, key-operated levers extending fore and aft of the machine located wholly forward of the type-bars and of less length than the height of the machine, constantly maintained operating 90 connections between the key-operated levers and their associated type bars foldable 95 at transversely aligned points adjacent the rear ends of the key-operated levers and the base of the machine, and a support for the key-operated levers foldable upwardly and rearwardly to an upstanding position 100 wholly in front of the type-bars.

In testimony whereof I hereunto affix my signature.

LEWIS B. BRIDGES.
